METHOD OF MAKING PLASTIC
BRIDGEWORKFrank J. Barth, Jamaica, N. Y., assignor of one-
half to Edward Fraundorfer, Rego Park, New
York

Application August 22, 1949, Serial No. 111,615

1 Claim. (Cl. 18—55.1)

1 This invention is concerned with a type of dental bridgework whereon artificial plastic teeth are molded and formed directly onto the metal framework and are securely anchored thereon by means of an ovoid threaded post integral with such framework. It particularly concerns the method of making such bridgework as well as a constructive casting investment tooth used in the making of such bridgework.

The advantages of such bridgework are obvious and many. In bridgework of this construction there is considerable strength in the bond of the teeth with the metal bridge frame whereby the possibility of the teeth becoming loose or out of alignment is negligible. Because of the perfect alignment of the teeth on the framework there are no food retaining pockets or crevices nor, because of the integral nature and strength of the bond of the teeth to the framework, is there any chance of the teeth loosening to create such pockets. Heretofore, cement has been used in securing artificial teeth to the bridgework. The use of cement made it most difficult to obtain a proper alignment of a tooth with the metal frame of the bridge. In time the cement gradually washed out causing loose teeth and creating food-retaining pockets.

Bridgework with artificial plastic teeth molded directly thereon as an integral part of the metal framework and in perfect alignment with such framework is obtainable through use of my constructive casting investment teeth. These investment teeth are fashioned of dental investment material, and are made in various sizes and shapes to permit making of all types of bridgework. The investment tooth serves as a guide in the casting of the metal frame of the bridge, and has a post hole for the casting of a threaded anchor post integral with the framework. The investment tooth further serves as a guide for the making of the finished plastic tooth and its accurate alignment on the metal frame of the bridge. The various steps involved in constructing the finished bridgework by means of this constructive casting investment tooth constitutes a decided improvement in the art.

Therefore, the general object of this invention is a dental bridgework wherein an artificial tooth of plastic is molded and formed in perfect alignment directly on the metal framework of a bridge, and is further secured thereon by means of a threaded anchor post integral with the framework.

Another object of this invention is a method of making such bridgework.

2

A more specific object of this invention is a constructive casting investment tooth that has a threaded ovoid post hole, and which tooth is useful in the making of bridgework.

Other advantages and other objects of this invention will appear as this specification unfolds in detail and as it is read in conjunction with the accompanying drawings, wherein a specific embodiment of the invention is illustrated.

- 10 In the drawings,
Fig. 1 represents a constructive casting tooth in perspective;
- Fig. 2 is a bottom view of the constructive casting investment tooth;
- 15 Fig. 3 is a cross section of Fig. 1 taken on line 3—3;
- Fig. 4 represents an investment tooth of the pontic type;
- Fig. 5 represents an investment tooth of the 20 facing type;
- Fig. 6 is an ovoid threaded post of wax;
- Fig. 7 is a side elevation view of a dentist's plaster mold impression of a lower portion of a patient's mouth with inlays in position and showing a molar space;
- Fig. 8 is a side elevation view with the investment tooth in position in the plaster model;
- Fig. 9 shows the plaster model as in Fig. 8, but with an index in position;
- 30 Fig. 10 shows the investment tooth as recessed preparatory to the casting of the metal framework for such;
- Fig. 11 shows the recessed tooth as waxed in;
- Fig. 12 is a view of the cast metal framework 35 inlaid in the plaster model with a wax tooth thereon and with the index in position;
- Fig. 13 is a view in perspective of the cast metal framework;
- Fig. 14 is a view in perspective of the finished 40 bridgework containing an artificial tooth of plastic molded and anchored thereon; and
- Fig. 15 is a view of an ovoid metal sleeve adapted to fit about the anchor post.

In the drawings there is shown in Fig. 1 a constructive casting investment tooth embodying my invention. This tooth is so called because it is used in the casting of the metal frame of a bridge as well as in the making of an artificial tooth of plastic. The tooth 1 is made of conventional dental casting investment material permitting it to withstand the high temperatures necessary in the casting of the metal frame for plastic bridge work. Extending vertically upwards into the tooth from its base 2 is an ovoid post hole 3. This post hole is provided with in-

ternal threads 4 or undercuts simulating threads. The purpose of the post hole, as will be later described, is to serve in the casting of a threaded ovoid anchor post 5 that is integral with the bridge framework 6. This post hole may be 5 round, but for best results the ovoid form is preferred because of the better anchoring qualities of the resulting cast ovoid post. The occlusal surface of the tooth is provided with cusps and sulci 7. The form of tooth illustrated in Fig. 1 10 as embodying my invention is characterized as of the tube type. Inasmuch as there are several distinct types of teeth used in the making of bridge-work, the investment tooth may take several forms, all, however, serving the same purpose. 15 Besides the tube type there are pontics 8 and facing teeth 9. The investment tooth may be made in the several types and in various sizes to enable the making of all types of bridgework.

It can be seen that suitable molds may be used 20 for making my investment teeth in large quantities, and that where a round post hole is to be made little difficulty will be experienced. But where an ovoid threaded post hole is desired, for lack of suitable means for making an ovoid threaded post hole, I prefer to first form an ovoid post of wax with suitable annular undercuts or threads as in Fig. 6. I then place dental investment material in a mold and around the ovoid wax post 10. Upon hardening of the investment 25 wax post 10. Upon hardening of the investment the wax post is then boiled out, leaving a threaded ovoid post hole 3 in the formed investment tooth 1.

In the use of the facing and pontic teeth 8, 9 the resulting metal bridge frame that is cast supports an artificial tooth substantially from the back of the tooth. For this reason the ovoid post hole 3 in these type of investment teeth is provided with a slot or rib opening 11 from the 35 post hole to the outside of the tooth.

It can be seen that there are many advantages in the making of dental bridgework through the use of my investment teeth. The investment tooth permits casting of an ovoid anchor post integral with the metal frame. The investment material of which the teeth are made is not only 45 inexpensive, but such material may be easily ground permitting accuracy of alignment of the finished tooth on the bridge frame. The investment tooth permits the making, and molding without cement of a finished plastic tooth directly 50 on the metal frame of the bridge. The finished bridgework obtained through the use of such investment teeth represents in the accurate alignment and strength of its parts a decided advance 55 in the art.

Through the use of my investment teeth I have devised an improved method in the making of plastic bridgework, whereby a plastic tooth is molded in accurate alignment directly onto the metal framework of a bridge and is anchored thereon by means of a threaded anchor post, 60 ovoid in form and integral with the metal frame of the bridge.

In the drawings, Fig. 7, there is shown a dentist's model 12 in plaster of the lower section of a patient's mouth with a molar space 13. The construction of a single-toothed plastic bridge-work by my improved method will now be described.

Inlays 14 are first made on the teeth 15 immediately adjoining each side of the molar space. A constructive casting tooth of the tube type 1 is selected of a size slightly larger than the space 13 to be filled. This tooth is ground down where

necessary to a proper position in the vacant space. Its sides 16 are made to contact the adjoining teeth; its base 2 is saddled as at 17 to rest upon and fit about the gum 18; its occlusal surface, where required, is ground so that its cusps and sulci 7 are in alignment with cusps and sulci of opposing upper teeth.

The tooth 1 is then given a bath in hot wax. This fills the post hole 3 with wax preventing foreign particles from accumulating therein. This wax treatment also hardens the exterior surface of the tooth preventing it from being worn down through constant handling. The resulting waxy surface also aids in permitting ready separation of the tooth from an index 19 that is made later on in the process.

The wax treated tooth 1 is next repositioned in the plaster model 12. An index 19 by usual methods is made of the tooth 1 in position. The index is taken of the crown 20 and the facing side 21 of the tooth. For obvious reasons the index 19 includes part of the adjoining teeth 15 with the inlays thereon. The importance of the index 19 lies, among other uses, in its use later on in the formation of a wax duplicate of tooth 1 as well as a finished plastic tooth. The index after being made is removed from the plaster model and saved for use later on in the forming of the duplicate wax tooth.

The gingival end 22 of the tooth 1, with the exception of the buccal or facing side 21, is next coated with wax. The thickness of the wax coating accurately predetermines the thickness of the metal framework that will be cast. This advantage of the investment tooth in serving as a means of predetermining the guage of the metal framework represents a decided advance in the art. Heretofore the alignment of the finished plastic tooth and metal framework was largely a matter of conjecture, and since there was nothing to wax against in preparation of the metal framework, the thickness of the framework was a matter of guessing and could not be accurately predetermined.

Prior to coating the gingival end 22 with wax, the sides 16 and the saddle 17 are slightly recessed as at 23. The sides 16 are recessed from the evident or vertical facing margin line 24 rearwards and upwards to the biting edge. Here the index 19 aids in accurately determining the evident line for recessing. The saddle is deepened slightly and the lingual or back side of the tooth is recessed from the saddle 15 up to the gingival line 25. The post hole and recessed portions of the tooth are then waxed in. The investment tooth as waxed in appears as in Fig. 11.

The investment tooth as waxed in is next invested with dental casting investment material. By conventional methods in the casting process the wax 26 is boiled out and replaced by metal to form the framework of the bridge. Because of the threaded anchor post 5 formed in the casting process, the investment tooth 1 is destroyed so as to remove it from the cast framework. The resulting cast framework as in Fig. 13 has a threaded vertical ovoid anchor post 5 integral with the frame. The cast metal framework is next connected in conventional manner to the inlays 14. This (Fig. 13) represents the completed framework of the bridge formed through the use of my investment tooth 1.

The next step is concerned with duplicating the destroyed investment tooth in wax, and subsequently reproducing and molding the wax tooth in plastic directly onto the metal framework 6.

The investment tooth 1, destroyed in the process of removing it from the metal casting, is next duplicated in wax directly on the metal framework 6, through use of the index 19 that had been previously made.

The metal casting 6 is positioned on the plaster model and the index 19 is placed in its original position on the model as in Fig. 12. Hot wax is then poured into the space between the index 19 and the metal casting 6 and about the anchor post 5. Upon cooling of the wax and removal of the index 19 the resultant wax tooth 27 represents a duplicate of the original investment tooth 1. Use of the index 19 in this step eliminates the heretofore difficult task of building such a wax tooth by hand.

The next step in the process is concerned with duplicating the wax tooth 27 in plastic. The bridge, which includes the metal framework with the wax tooth thereon is next invested with dental investment material by conventional methods. By a known process the wax tooth is boiled out and reproduced in plastic. It is to be noted that such plastic tooth 28 is not reproduced independently of the metal framework, but rather is produced or duplicated directly on the framework and about the ovoid anchor post 5.

The plastic material used in forming the finished tooth is that conventionally used in dental practice, and is preferably acrylic plastic.

Upon removal of the investment material we have a completed bridgework as in Fig. 14. The completed bridgework 29 has a finished acrylic plastic tooth 28 molded to the framework in perfect alignment and anchored thereon by the threaded anchor post 5.

It is to be noted that in the making of such bridgework 29 a tube type investment tooth 1 was used. In those cases where a facing tooth 9 or a pontic tooth 8 is required in making the bridge the process is the same. However, in preparing the facing and the pontic investment teeth for the metal casting, the post hole 3 and the backing 30 of the facing tooth are waxed up, while in the case of the pontic tooth the post hole 3, the backing 31 and an occlusal surface are waxed up. The resultant metal castings of the pontic and facing investment teeth will be the duplicate of the waxed in sections.

Because of the plastic material of which the finished teeth are formed, and since such teeth are molded and securely anchored onto the metal frame of the bridge, there is little chance of such teeth becoming loose. However, for various reasons a tooth may become damaged necessitating

its replacement. In such case after the damaged tooth is removed, a smooth sleeve of metal 32 is placed over the anchor post to block out the threads. An impression is taken in conventional manner. A finished acrylic tooth formed from the impression is cemented onto the bridge without necessitating the removal of the bridge frame from the patient's mouth. It can be seen that not only does the post 5 serve to anchor a finished tooth to the framework, but it serves the added advantage of making such teeth interchangeable.

Having described my invention above, it is my intent, however, to claim such invention not only as described, but also in all such forms and variations as may reasonably be construed to be within the spirit of the invention and within the scope of the appended claim.

I claim:

20 A method of constructing plastic bridgework through use of an investment tooth having a threaded post hole, whereby such method a completed bridge is formed including the metal frame and a plastic tooth molded onto such frame and bound thereon by a threaded anchor post, and 25 such method comprising positioning in a vacant dental space of a plaster model an investment tooth that has a threaded ovoid post hole, taking an index of the occlusal surface and evident facing sides of such tooth in position, recessing 30 the saddle, the back of such tooth to the gingival line, and the sides from the saddle to the biting edge, waxing in the post hole and the recessed portions including the saddle, casting a metal frame of such waxed in sections, duplicating the 35 original investment tooth onto such metal frame in wax, reproducing such wax tooth in plastic onto the metal framework.
